UNITED STATES PATENT OFFICE.

PATRICK H. HICKMAN, OF IRVINGTON, NEW JERSEY, ASSIGNOR OF ONE-HALF TO
THOMAS ALOYSIUS HICKMAN, OF IRVINGTON, NEW JERSEY.

LAST.

1,237,645.

Specification of Letters Patent. Patented Aug. 21, 1917.

Application filed December 30, 1914. Serial No. 879,742.

To all whom it may concern:

Be it known that I, PATRICK H. HICKMAN, a citizen of the United States, residing at 995 Clinton ave., Irvington, in the county of 5 Essex and State of New Jersey, have invented certain new and useful Improvements in Lasts, of which the following is a specification.

The present invention relates to lasts and 10 more especially to shoe lasts.

The primary object of the invention is the provision of a shoe last comprising two movable sections designed for the purpose of contraction and expansion, in order that the 15 same can, when contracted, be readily inserted within a shoe, boot or the like and then expanded for the purpose of stretching the article in which it is disposed.

Another object of the invention is the provision of a last such as described which embodies means for retaining the movable sections thereof in their contracted position.

A further object of the invention is the provision of a last including two movable 25 sections, which are so constructed at the meeting edges thereof that the same will engage at all points, consequently preventing weakening when strain is necessitated in expanding the same when the said last is positioned within a shoe.

Still another object of the present invention is the provision of a last including two movable sections, with means positioned therein for movably connecting said sections 35 and limiting their movements in one direction, the said last being provided with contacting shoulders for limiting the movement of the sections in the opposite direction.

A further object of the present invention 40 resides in the provision of a last, which will be comparatively simple and inexpensive to manufacture, reliable and efficient in use, and readily operated.

With the above and other objects in view 45 the present invention consists of the novel features of construction, formations, combinations and arrangements of parts to be hereinafter more particularly described, claimed, and illustrated in the accompanying 50 drawing, it being understood that various minor changes in the specific details of construction can be resorted to within the scope of the appended claims, without de-

parting from the spirit or sacrificing any of the advantages of the invention. 55

In the accompanying drawing forming a part of this application:

Figure 1 is a side elevation of the last partly in section, showing the same extended. 60

Fig. 2 is a similar view showing the same contracted.

Fig. 3 is a bottom plan view thereof.

Fig. 4 is a view showing in plan and side elevation, the sleeve. 65

Fig. 5 is a detail view of the locking ball.

Fig. 6 is a similar view of the spring, and

Fig. 7 is a view showing the latch plate in edge and side elevations. 70

Referring to the accompanying drawing by similar characters of reference to illustrate corresponding parts throughout the several views, the numeral 8 denotes in general my improved last which comprises a toe section 9 and heel section 10. The meeting edges of these sections 9 and 10 are preferably convex and concave respectively as at 12 and 11 so that they will be at all times in engagement as the heel section is moved from the position shown in Fig. 1 to the position 80 shown in Fig. 2, thereby eliminating all strain when the last is placed within a shoe and moved to extended position. The heel section 10 of the last is provided with an opening or socket, which opens through the upper side thereof and receives a bushing 13 which prevents any undesired wearing of the heel section when the last is placed upon its stand or other means of support. 85

The curved surfaces 11 and 12 of the heel 90 and toe sections are provided with angularly disposed abutting shoulders 14 and 15 which limit the relative movement of the sections 9 and 10 when the said last is contracted, while the opposite end of the curved surface 95 12 terminates in the transverse lip 16 which engages the underside of the heel section 10 limiting the movement thereof when the said last is extended.

Recesses 17 and 18 are provided in the 100 meeting edges of the sections 9 and 10. The recess 18 is preferably of an inverted L shape comprising angularly disposed channels 19 and 20. A hinging plate 21 is rigidly secured within the channel 19 as shown at 22 105 and projects into the recess 17. The plate 21

is formed with slots which curve to conform to the curvature of the surfaces 11 and 12. Pins 23 are secured within the toe section extending transversely of the recess 17 and 5 through the slots 22, and form means for movably connecting the sections 9 and 10. It should be noted that the slots 22 are of sufficient length to permit of the proper movement of the heel section 10 relative to 10 the toe section 9.

A plate 24 is secured within the channel 20 engaging the upper side of the plate 21 and projecting into the recess 17. This plate assists in holding the sections in their contracted position as will presently be explained and will be hereinafter termed a latch plate for the purpose of distinguishing it from the before mentioned plate 21.

A pin 25 passes through the outer end of 20 the latch plate 24 firmly retaining the same within the channel 20, while a similar pin 26 passes through the inner end of this plate for pivotally connecting the latter to the toe section 9. A split sleeve 27 is disposed within 25 the recess 17 and has alining apertures 28 and 29 formed in the opposite ends thereof and notches 30 for permitting the insertion therein of the adjacent end of the latch plate 24. The pin 26 which supports the latch 30 plate 24 passes through the opening 29 while the opposite end of the sleeve is held rigid relative to the section 9 by a pin 31 which passes through the apertures 28. The inner end of the latch plate 24 has its upper corner cut away forming a seat 32 for engagement with a ball 33 when the last is in its contracted position while a spring 34 is disposed within the sleeve 27 in engagement with the pin 31 and ball 33 serving at all 35 times to yieldingly force said ball against the curved seat 32 for the purpose of automatically forcing the heel section upwardly and the shoulders 14 and 15 into engagement and further for retaining them in this 40 position.

It will be noted that the front corners of the heel section are rounded as at 35 while the rear corners of the toe section are extended slightly to form a channel 36 in 50 which the adjacent end of the heel section

is received. This arrangement holds the sections 9 and 10 against any undesired lateral movement.

From the foregoing disclosures it will be manifest that a last is provided which will 55 fulfil all of the necessary requirements of such a device.

Having thus fully described my invention what I claim as new and desire to protect by Letters Patent is:

1. In a last, a heel section having a recess therein, a toe section having a relatively large recess therein, a plate hingedly connecting said sections together, a relatively long lever fixed at one of its ends in the recess of the heel section and projecting into the recess of the toe section, the greater portion of said lever lying in the latter recess, a sleeve confined in the inner end of the recess of the toe portion and having pivotal connection with said lever, said lever having its end which is pivotally connected to said sleeve provided with a seat which is confined within said sleeve, a ball disposed within said sleeve and engaging said seat, and a spring within the sleeve adapted to engage the ball to force the latter normally into engagement with said seat. 65

2. A last comprising two expandable and contractible sections, one of which has a relatively deep recess, a relatively long lever rigidly connected to one of the sections and having the greater portions of its length extending into the recess of the other section, a sleeve mounted in the recess of said recessed section and having pivotal connection with said lever, the lever adjacent its point of pivotal connection having a seat which is confined within said sleeve, and a spring 70 pressed ball confined within the sleeve and adapted to be normally located in the seat of said lever to force said sections normally 75 in their contracted position. 80

In testimony whereof I affix my signature in presence of two witnesses.

PATRICK H. HICKMAN.

Witnesses:
